UNITED STATES PATENT OFFICE

154,085

DESIGN FOR A QUARTER BOOT

Arthur E. Warren, Des Moines, Iowa

Application November 14, 1947, Serial No. 142,535

Term of patent 7 years

(Cl. D38—11)

To all whom it may concern:

Be it known that I, Arthur E. Warren, a citizen of the United States and resident of Des Moines, in the county of Polk and State of Iowa, have invented a new, original, and ornamental Design for Quarter Boots, of which the following is a specification, reference being had to the accompanying drawing, forming part thereof.

Figure 1 is a front elevational view of a quarter boot, showing my new design.

Figure 2 is a top plan view of the same.

Figure 3 is a side elevational view and Figure 4 is a bottom plan view of Figure 3.

I claim:

The ornamental design for a quarter boot, as shown.

ARTHUR E. WARREN.
